UNITED STATES PATENT OFFICE.

CARL W. JENSEN, OF WINIFRED, MONTANA.

METHOD AND APPARATUS FOR CONDUCTING MINING OPERATIONS.

1,332,986.

Specification of Letters Patent.

Patented Mar. 9, 1920.

Application filed April 24, 1919. Serial No. 292,437.

To all whom it may concern:

Be it known that I, CARL W. JENSEN, a citizen of the United States, residing at Winifred, State of Montana, have invented 5 new and useful Improvements in Methods and Apparatus for Conducting Mining Operations, of which the following is a specification.

This invention relates to methods and apparatus for conducting mining operations, having for one object to provide means of a simple and improved nature for moving masses of earth, ore, etc., from the mine with the expenditure of a minimum amount of 15 physical labor.

A further object of the invention is to provide means whereby the laborious task of shoveling and conveying quantities of ore, etc., in wheelbarrows or other such receptacles may be dispensed with, and by the use 20 of which the ore production is materially increased and the amount of labor diminished.

A still further object of the invention is to provide means whereby the earth blasted or 25 dug within the mine chamber is delivered directly to a movable receptacle, and whereby this receptacle may be so operated as to empty its contents so as to be distributed to other parts of the mine for further 30 operation or treatment.

With these objects in view, together with others which will appear as the description proceeds, the invention resides in the novel construction, combination and arrangement 35 of parts, all as will be described more fully hereinafter, illustrated in the drawings, and particularly pointed out in the claims.

In the drawings:

Figure 1 is a vertical sectional view taken 40 through a mine of conventional form and illustrating the application of an apparatus constructed in accordance with the invention,

Fig. 2 is a horizontal sectional view taken 45 just above the mine floor,

Figs. 3 and 4 are detail sectional views of the conveyances used in carrying out the invention and illustrating the manner in which the conveyances are moved and dumped,

Fig. 5 is a detail perspective view of one 50 of the conveyances.

Fig. 6 is a rear elevation of the conveyance,

Fig. 7 is a view similar to Fig. 1 and illustrating the application of the invention to 55 a mine drift,

Fig. 8 is a diagrammatic perspective view of a conveyance and moving apparatus therefor of slightly modified form.

Fig. 9 is a sectional view on line 9—9 of 60 Fig. 2,

Fig. 10 is a view similar to Fig. 1 and illustrating a slightly different way in which 65 stope mining may be carried out in accordance with the invention, and

Fig. 11 is a plan view illustrating a modified form of winding apparatus for causing the dumpers to move.

In carrying out the invention, the studding employed to support the roof of either 70 the stope or the drift is arranged so as to provide passages transversely of the level or gallery, and it is my intention to employ the passages thus formed for the accommodation of conveyances or dumpers to carry 75 the mined earth from various points in the passages to the grizzly. These conveyances or dumpers are of substantially scoop-like construction, and rest upon the floor of the stope or drift. These conveyances may be 80 arranged in the stope prior to the blasting operation, so that the material loosened by blasts will drop either into the conveyance or in the path of the latter. When the conveyances are filled, suitable draft apparatus 85 is employed to drag the same forward toward the grizzly, whereupon the conveyances are tilted in such a manner as to deposit their contents into the grizzly to be delivered to cars or conveyances in galleries 90 below. The conveyances used in delivering the mined ore to the grizzlies may be moved in any approved manner, and the invention contemplates means whereby these conveyances may be moved forward or backward 95 without the employment of manual labor.

By the use of such mechanism, it is obvious that the laborious task of wheeling the mined ore from the rear ends of the stopes or drifts to the grizzlies is eliminated, and 100 a great quantity of ore may be mined and delivered to the grizzlies with a minimum amount of labor.

Referring now to the drawings, 10 indicates the conventional mine gallery or level, 105 11 the grizzly, and 12 an overhand stope. The gallery 10 has the usual mine car track to permit of the cars passing thereover, this track being indicated at 13.

The studding in the stope is indicated at 110 14, and connects with the roof beams 15 as shown, and the studding is arranged within

the stope in such manner that passages are formed between the various rows of studding transverse to the gallery 10. It will be understood that as the mining operations progress in the particular stope, the studding will be erected. The studding in each row is connected at its lower ends by the planking 16, and these planks form guide strips for the conveyances to be hereafter fully described. The conveyances in the preferred embodiment of the invention comprise the scoop-like structures indicated generally at 17, and these conveyances are of such width as to slide freely within their respective passages and yet not to bind therein. The scoops are provided with upstanding side walls 18 suitably braced as shown, and the rear end of each scoop has hinged thereto a door or gate 19. The doors 19 are suitably braced upon their rear faces as indicated at 20, and, if desired, the bottoms of the scoops may be provided with longitudinally disposed supporting ribs 21. It may be found necessary to employ means between the sides of the receptacles or conveyances and the planking 16 in the mine stope to minimize friction, and rollers indicated at 22 in Fig. 5 may be used for this purpose. These rollers will be mounted in suitable brackets upon the scoop sides.

Each door 19 has pivotally connected at its upper end as at 23 one end of a short cable or link 24, and this link is preferably of a length equal to that of the scoop. The forward end of the link is provided with an eye 25 adapted to receive a hook 26 upon the free end of a cable 27, the latter passing through an eye 28 in the forward end of the scoop. This cable 27 is connected to a drum 29 constituting a part of a windlass arranged upon a car 30 upon track 13 in the level or gallery. It will be observed that the cable 27 and link 24 are disposed at substantially the longitudinal center of the scoop.

In operating the improved ore conveyer, the scoop or conveyance is positioned in the passage beneath the earth or material to be mined, and the door or gate 19 at the rear end of the conveyance rests against the rear wall of the passage, as shown in Fig. 1. The material is then mined by blasting or otherwise, and drops into the conveyance, as will be understood. The gate at the rear end of the conveyance will prevent the rock falling behind the conveyance. After the blasting or earth loosening operation, the cable 27 passing through eye 28 and connected to the forward end of link 24 is tensioned by operating the windlass. The initial movements of the windlass will cause the gate 19 to move to closed position, and further winding of the cable will cause the conveyance to slide forwardly upon the floor of the passage. When the forward end of

the conveyance nears the grizzly, the hook 26 in the cable is detached from eye 25 in the link and is then detached from the eye 28. The hook 26 is then reengaged in eye 25 of the link, whereupon further winding of the drum 29 will cause the pull to be directed upon the door or gate 19. A stop or abutment 31 is arranged in the path of the conveyance at the edge of the grizzly, and tightening of the cable 27 will cause the conveyance to ride up at its rear end as shown in Fig. 4; the stop 31 acting as a fulcrum for the scoop. The contents of the scoop will, when the scoop reaches the proper inclination, slide forwardly into the grizzly, whereupon such contents is distributed to the level or levels below. Any material conveyed by the scoop which is of such bulk as can not pass through the grizzly may be broken up by the mine operators. After the contents of the scoop has been dumped, the said scoop may be moved rearwardly in the stope for further use.

To prevent the mined ore lodging in the channels formed between the planking 16 upon the studding, suitable covers such as the boards or planks 32 may be placed upon the upper edges of the planks 16 between the various stanchions 14.

After the conveyance has been dumped in the manner described, it may be moved back for further use manually, or a device such as that indicated in Fig. 8 may be employed for this purpose. In the figure mentioned, 29 indicates the drum of the windlass, and a cable 33 is wound thereon in a direction opposite to the winding of cable 27. The cable 33 passes over a pulley 34 suitably secured within the passage and above the floor thereof, and the free end of this cable is connected as by means of a hook 35 to the eye 28 at the forward end of the scoop. It is obvious, therefore, that when cable 27 is tensioned the conveyance will move forwardly, while the cable 33 will pay out. Reverse movement of the drum 29 will cause the cable 33 to be wound upon the drum while the cable 27 is paid out. This simple apparatus permits of the conveyance being readily moved in either direction.

In Fig. 7 of the drawings the invention is illustrated as applied to a conventional drift, and in this instance prior to the digging or blasting operation the door or gate 19 is dropped at the rear of the drift so as to receive the ore broken from the wall thereof. To eliminate the possibility of a dead center between the eye 23 and the windlass, 120 a block or beam 33' may be placed upon the floor of the drift beneath the said gate. The operation of the apparatus in drift mining is similar to that described in connection with stope mining above defined. 130

In Fig. 10 there is illustrated a modification showing how stope mining may be carried on as the depth of the mine increases. As the stope is cut away the floors therein are moved up, as is familiar to those acquainted with such mining operations. In such instances, the cars or carriages containing the winding apparatus are moved to the floor directly below the miner's floor, as are the buckets or conveyers to be employed in transporting the ore to the chute. The miner's floor may be provided with removable sections as indicated at 50, and the conveyers 17 are moved beneath the removable sections of the miner's floor to receive the ore dislodged or broken away by the blast. After the blast the dumper or conveyers may be operated by the windlass to move the same forwardly to the chute. At 51 in Fig. 20 10 the forward end of the slideway for the dumper is shown cut away so as to permit of the dumper tilting therein to deliver its contents to the chute.

When using the apparatus in this manner, 25 the car 30 may be provided with a pair of winding drums 52 and 53, which are loosely mounted upon the supporting shaft 54. This shaft is provided near one end with a pinion 55 in mesh with gear 56 affixed to the drive 30 shaft of motor 57. The shaft 54 is provided with clutches 58 and 59, which may be operated by the link mechanism 60 to move alternately into engagement with their respective winding drums. The cable 61 on drum 35 52 passes over pulley 63 secured in the ceiling of the mucker's floor and near the rear end thereof, and this cable then passes forwardly and downwardly and is connected as at 64 to the forward end of the dumper. The 40 cable 65 upon drum 53 is connected to the hinged door 19 at the rear end of the dumper. With the clutches in the position shown in Fig. 11, operation of the motor will cause the cable 61 to be wound upon its drum 52, 45 while drum 53 is free to unwind. Winding of the cable 61 causes the dumper to be moved rearwardly until positioned at the rear end of the stope. The motor is then stopped, and after the dumper 17 has been 50 filled with ore the clutch 59 is moved into engagement with drum 53 and the motor is started. This operation causes cable 65 to be wound upon drum 53, first moving door 19 to raised position, and then pulling the 55 dumper 17 forwardly, the cable 61 paying out during such operation. The dumper 17 moves down inclined surface 51 the proper distance to cause the contents thereof to be discharged into the chute.

60 From the foregoing it is obvious that I have provided means of a simple nature for carrying out successfully the mining operation, and one in which the use of manual labor is to a great extent eliminated or reduced. The conveyances may be made in

various sizes, depending largely upon the character of the mining operations to be performed, as well as the size and construction of the passages formed between the studding. In instances where the passages 70 between the rows of studding are tortuous, it will be understood that guide means for the draft cable 27 will be employed in the passages.

While the above is a description of the 75 preferred embodiment of the invention, it is to be understood that the invention is not necessarily limited thereto, as various changes in the minor details of construction and arrangement of parts may be resorted 80 to without departing from the invention as defined by the claims.

Having thus fully described my invention, I claim:—

1. The method of mining which consists 85 in forming roof supports in a drift or stope in such manner as to provide partitions subdividing the drift or stope into passages arranged transversely to the level or gallery, arranging between said passages and the 90 level or gallery a dump passage leading to the gallery or level below, arranging conveyances in said passages movable along the floors thereof between the mining and dumping points, breaking down the material in 95 the passages and filling the conveyances therewith, moving said conveyances by means under control from the level or gallery from the mining to the dumping point, and then dumping the contents of the 100 conveyances into the dump passage for travel to the gallery or level below.

2. A mining apparatus comprising a receptacle disposed adjacent to the material to be mined to receive such material, a windlass in the path of said receptacle and beyond the latter, a stop interposed between the receptacle and the windlass, and a cable on the windlass to be connected to said receptacle.

3. A mining apparatus comprising a plurality of receptacles arranged adjacent to the material to be mined to receive the same, guide doors on said receptacles to direct material thereinto, a draft cable to be connected 115 to each door, and a stop in the path of said receptacles.

4. In a mining apparatus, a conveyance arranged upon the floor of the drift or stope and adapted to receive the material 120 mined, a door hingedly connected to one end of the conveyance, a link connected to said door, an eye secured to said receptacle below the point of connection of the link with the door, a draft cable detachably connected to said link and passing through said eye, and a stop in the path of said conveyance.

5. In a mining apparatus, a conveyance 130 slidably arranged within a drift or stope,

a gate horizontally hinged upon said conveyance at the rear end thereof, an eye at the forward end of said conveyance and at the bottom thereof, a link connected at one 5 end to said door, an eye at the opposite end of said link, the said link being of substantially the same length as the conveyance, a draft cable, a hook at one end of said cable, the said cable being passed through the eye 10 at the forward end of said conveyance and engaged with the said link eye, and a stop in the path of said conveyance.

6. In a mining apparatus, a grizzly arranged between a stope or drift and a level, 15 a stop adjacent to said grizzly and in the stope or drift, a conveyance arranged within the stope or drift to receive the material mined, and means within the level for moving the conveyance into engagement with 20 the stop.

7. In a mining apparatus, a mucker's floor, a miner's floor disposed above the mucker's floor, said miner's floor having removable sections, a carrier slidably arranged upon the 25 mucker's floor and beneath the said removable sections of the miner's floor, and means for moving the carrier in two directions.

8. In mining apparatus, a movable carrier, a movable body having a motor thereon, a shaft operatively connected with said 30 motor, drums loosely mounted on said shaft, clutches adapted to alternately engage with the said drums, a cable on one of said drums connected to the carrier to move the latter in one direction when the drum shaft is rotated, and a cable on the other drum connected to the carrier to move the latter in the opposite direction when the shaft is rotated.

9. In a mining apparatus, a grizzly arranged between a stope or drift and a level, 40 a stop adjacent to said grizzly and in the stope or drift, a conveyance arranged within the stope or drift to receive the material mined and having a guide door to direct the 45 material thereinto, and means within the level for closing the door of the conveyance, and moving said conveyance into engagement with the stop and tilting the conveyance to discharge the material into the 50 grizzly.

In testimony whereof I affix my signature.

CARL W. JENSEN.
